THE NATIONAL LITHOGRAPHING COMPANY,
WASHINGTON, D. C.

UNITED STATES PATENT OFFICE.

HARRY T. JOHNSON, OF NEW YORK, N. Y.

ELECTRIC DOOR-OPENER.

SPECIFICATION forming part of Letters Patent No. 508,518, dated November 14, 1893.

Application filed May 19, 1893. Serial No. 474,745. (No model.)

To all whom it may concern:

Be it known that I, HARRY T. JOHNSON, a citizen of the United States, and a resident of the city, county, and State of New York, have 5 invented certain new and useful Improvements in Electric Door-Openers, of which the following is a full, clear, and exact description, reference being had to the accompanying drawings, forming part of this specification.

10 My invention relates to that class of electric locks popularly called door openers, which are generally applied to the main doors of flats and apartment houses, and which, through the agency of an electric magnet operated from the different rooms or apartments 15 in the building, may be actuated to release the latch of the door and permit it to be opened.

The class of apparatus to which my invention pertains has generally comprised a movable latch block or keeper for the latch, normally locked to hold the latch and prevent the door from being opened, an electro magnet operated by circuit closing devices arranged as desired at different points in the 25 building, and mechanism intermediate the armature of the magnet and the latch block by which, when the circuit through the magnet is closed and its armature attracted, the latch block is unlocked and may be rotated 30 sufficiently to release the latch when pressure is applied to the door, and suitable devices, such as retractile springs, to return the parts to their normal position when the circuit through the magnet coils is broken. The 35 mechanism just described has usually been secured to the door jamb in a position to cooperate with the reciprocating latch carried by the door, and so constructed as to be immovable from the outside of the door in a 40 manner well understood. In order that such mechanism may be operative, it is absolutely necessary that the door should be moved sufficiently to start the latch block from its normal position before the intermediate locking 45 mechanism returns to its locking position, and to meet this requirement, various mechanical devices have been employed, the one most generally in use consisting of a spring pressed plunger secured to the door or the jamb, and 50 arranged to exert a constant pressure against the door, so that when the locking mechanism is disconnected or disengaged from the

latch block, the spring will throw the door open sufficiently to start the latch block from its normal position, and thus prevent the return of the locking mechanism to its normal 55 position until the door latch has been pushed entirely clear of the latch block or keeper; but these devices have not proved entirely satisfactory. They are unreliable, particularly in wet weather, when the door will often stick, and the pressure of the spring be insufficient to release it; and furthermore, they deface the door or the casing and increase the 60 number of parts required to put the apparatus in working condition.

The principal object of my invention is the provision of means for overcoming these objections, and a further object thereof is the provision of novel mechanism for actuating 70 the latch releasing devices, whereby I attain simplicity of construction, strength of parts, and positive and reliable action thereof.

To these ends my invention consists in the combination with mechanism for releasing the 75 latch block or keeper, of a permanent magnet for holding such mechanism out of its locking position until released by the movement of the door.

It also consists in the novel details of construction and combination and arrangement of parts hereinafter described and specifically pointed out in the claims.

In the accompanying drawings, Figure 1 is a view in elevation showing my improved apparatus inserted in a door jamb. Fig. 2 is a similar view showing the parts in a different position. Fig. 3 is a cross section on the line 3—3 (Fig. 1). Fig. 4 is a cross section on the line 4—4 (Fig. 2). Fig. 5 is a similar view showing the armature about to be moved, by the movement of the latch block, from the position it occupies when in contact with the permanent magnet. Fig. 6 is a cross section on the line 6—6 (Fig. 1) showing a modified construction, and Fig. 7 is a partial view in elevation showing another modification.

The form of mechanism which at the present time I preferably employ is illustrated in Figs. 1 to 5, but many modifications may be made therein, some of the most obvious being illustrated in the other views.

It will also be understood that my invention may, in view of the following description

thereof, be applied to most of the door openers now in common use without the exercise of more than ordinary mechanical skill.

In the form of apparatus shown in Figs. 1 to 5 A represents the jamb or casing of the door, which is mortised to receive the supporting frame B of the apparatus. The frame B is provided with a face plate of the usual form which is flush with the door jamb, and it is also constructed with a web b, which serves as a support for one end of the pivots on which the operating mechanism is mounted. The latch block or keeper C is mounted on the pivot c, and is normally held in the position shown in Figs. 1 and 3 by the spring c'. The latch block may if desired be provided with the striking roller c². A link D is pivoted at one end to the inner edge of the latch block C, and at the other end to the swinging end of the link D'. The opposite end of the link D' is pivotally secured to the frame B. The links D and D' thus form a toggle joint which, when straightened out, and the locking lever E, to be presently described, is in its normal position, will hold the latch block C firmly in position and prevent the release of the latch F. The inner end of the link D is provided with a toe d which, when the toggle joint is straightened out or extended, as shown in Figs. 1 and 3, will rest against a stop d' formed on the link D', and prevent the toggle from swinging over its center. The locking lever E is pivoted in the frame B, and a spring e tends to swing its lower end toward the link D'. The lower end of the lever E is notched or rabbed to fit over the swinging end of the link D', in which position it is normally held by the spring e, thereby normally locking the toggle in its extended position (shown in Figs. 1 and 3) and preventing the latch block from rotating to release the latch. The locking lever E is also provided with an arm e' which projects into the path of the pivoted armature G which is arranged in proximity to the poles h of the electro magnet H, and which is attracted thereto when the coils of said magnet are energized by closing the circuit. The locking lever E is also provided with an extension e² which is moved into the path of the rotating latch block C, so that when the latter is rotated, the lever E and arm e' will be moved thereby, as will be more fully herein-after explained.

The means employed by me for holding the mechanism above described out of its locking position until released by the movement of the door, is a permanent magnet, and preferably I form such permanent magnet by connecting the poles h of the electro magnet in magnetic contact with a plate or bar I of hard steel which forms a permanent magnet, so that the said poles h serve as polar extensions of the permanent magnets, as well as for the poles of the electro magnet, the result being that when the armature G is attracted to said poles by the closing of the circuit through

the coils of the electro magnet, the attraction exerted by the permanent magnet will hold it there after the coils of the electro magnet are de-energized by the interruption of the current, and until it is mechanically released, as hereinafter set forth. A spring g tends to hold the armature G away from the poles of the magnets, but this spring, while of sufficient strength to hold the armature in the position shown in Figs. 1 to 4 when the coils of the electro magnet are de-energized, is not strong enough to resist the attractive force thereof when the circuit is closed, or the attraction of the permanent magnet when the armature is in contact with the poles h. The coils of the electro magnet are included in a circuit comprising a primary battery or other source of electrical energy, and circuit closing devices located where desired in the different rooms or apartments of the building, in the usual way.

The operation of my improved device, as herein illustrated, is as follows: The door being closed, the latch F lies behind the latch block C, and the different parts of the mechanism are in the position shown in Figs. 1 and 3. The latch F is of the well known construction which cannot be reciprocated from the outside, and the door is therefore firmly locked so long as the latch block C is held in said position. When it is desired to release the latch from any station in the building, the circuit closing device, which is usually an ordinary push button, is manipulated to close the circuit through the coils of the electro magnet H. The armature G is then attracted toward the poles h of the magnet, and in its movement strikes the end of the arm e' secured to the locking lever E and carries the notched lower end of the lever E clear of the inner end of the link D'. The closing of the circuit carries the armature G into contact with the poles h, and it is held there by the attractive force of the permanent magnet after the circuit is broken. The lever E is thereby held out of engagement with the toggle link D', and if pressure be applied to the door, the latch F will engage with the latch block C and rotate it in the direction to release the latch. Before the latch block is thus rotated sufficiently to release the latch entirely, its inner edge will strike the extension e² on the locking lever E, and the further rotation of the keeper by the inward movement of the door will swing the locking lever E and arm e' inwardly, and the arm e', which rests against the armature G as shown in Fig. 5, will force it out of contact with the poles h, and under the action of spring g it will return to its normal position as shown in Figs. 2 and 4. As soon as the contact between the armature and the poles h is thus broken, the locking lever E will, under the action of spring e, swing inwardly beyond the position shown in Fig. 3 to that shown in Fig. 4. In this manner the mechanism by which the latch block is locked and unlocked,

is, by the movement of the door, released from the position in which it is held by the permanent magnet. The further movement of the door will rotate the latch block C sufficiently to release the latch F entirely. As the latch clears the latch block, the spring c will cause the latter to return toward its normal position, and as it swings into place, the links D, D', straighten out. As the link D' thus swings back toward its normal position, the swinging end thereof presses against the side of the locking lever E, which is thereby carried toward the latch block C until the said end of link D' registers with the notch formed in the lower end of lever E, when the spring e will throw the lever back so that the notch will swing into place over the end of the link D', and the parts will be locked so that when the door is closed it will be locked as before, and will remain locked until the circuit through the magnet coils is again closed, when the operation above described will be repeated.

It will be observed that I have entirely obviated the necessity for providing any mechanical device for throwing the door away from its jamb simultaneously with the closing of the circuit, because in my device the permanent magnet holds the locking lever out of its locking position until the door is moved, irrespective of the length of time that may elapse between the breaking of the circuit through the electro magnet, and the moving of the door, and this highly desirable result is obtained without the employment of any mechanism except the small piece of steel required for the permanent magnet, which operates automatically without friction, which requires no careful adjustment, and which will never need repairs or readjustment.

As previously stated, many modifications may be made in the details and mechanical features of the apparatus without departing from the spirit of my invention, and in Figs. 6 and 7 I have illustrated two modified arrangements of the magnets.

In Fig. 7 instead of connecting the magnetized bar or plate I to the poles h, which also serve as the poles of the electro magnet, I accomplish the same result by mounting a separate permanent magnet J of the horse shoe or other form over the electro magnet in such a position that the armature G will contact with its poles when it is attracted by the electro magnet.

In Fig. 6 is illustrated still another modification, in which the pivoted armature G is made of hard steel instead of soft iron, as in the form of apparatus first described, and serves as the permanent magnet. It will also be understood that one or both of the cores of the electro magnet may be of hard steel, in which case they will form a permanent magnet. These modified forms of apparatus operate in the same manner as that form of which I have already given a detailed de-

scription, so that no further description thereof is necessary.

It will of course be understood by those skilled in the art that the permanent magnets are constructed of hard steel such as is usually employed for permanent magnets, and although it may be done if desired, it is not at all essential that they should be magnetized before being placed in the apparatus, because, by contacting with the poles of the electro magnet when the coils thereof are active, they will immediately become permanently magnetized. Thus if the parts I have designated as permanent magnets are not permanent magnets when placed in position, they will become such the first time the apparatus is used.

Besides the advantages derived by the employment of the permanent magnet for holding the locking mechanism out of its locking position, until the door is moved, as herein set forth, the mechanical details and arrangement of parts which I herein show and preferably use, possess decided advantages in that the construction is strong, durable, and so simple that the apparatus is not likely to get out of repair, and will operate promptly, and reliably on a comparatively feeble current.

Having thus described my invention, what I claim as new, and desire to secure by Letters Patent, is—

1. In a door opener, the combination of a movable latch block, mechanism for locking and unlocking the same, an electro magnet for actuating said mechanism to unlock the latch block, and a permanent magnet for holding said mechanism out of its locking position until released by the movement of the door, substantially as shown and described.

2. In a door opener, the combination of a movable latch block, a lever for locking and unlocking said latch block, an electro magnet arranged to throw said lever out of its locking position and into the path of the latch block when the current is applied, and a permanent magnet arranged to hold said lever in its position in the path of the latch block until released from said position by the movement of the latch block, substantially as shown and described.

3. In a door opener, the combination with an electro magnet having a pivoted armature, of a pivoted latch block, a spring pressed lever for locking and unlocking said latch block, which lever lies in its locking position in the path of the pivoted armature, and in its unlocking position in the path of the pivoted latch block, and a permanent magnet for holding said lever in its unlocking position until moved therefrom by the movement of the latch block, substantially as shown and described.

4. In a door opener, the combination of a pivoted latch block, a toggle joint connected at one end to the latch block, and at the other

end to its supporting frame, a spring pressed lever normally engaging with said toggle and locking the same in an extended position, an electro magnet arranged to move said lever from its locking position and into the path of the latch block when the current is applied, and a permanent magnet for holding the latch block in the position to which it is moved by the electro magnet until released from such position by the movement of the latch block, substantially as shown and described.

5. In a door opener, the combination with a movable latch block, of an electro magnet having its poles secured to a permanent magnet, and mechanism intermediate the electro magnet and the latch block for unlocking the latch block when the coils of the electro mag-

net are energized, substantially as shown and described. 20

6. In a door opener, the combination of the pivoted latch block, a toggle joint, one member of which is secured to the latch block and the other member to the frame, a lever engaging with said toggle so as to lock the same 25 when the latter is in its extended position, an electro magnet, an armature therefor normally disconnected with said locking lever, but arranged to engage therewith and throw it out of engagement with the toggle when 30 the magnet coils are energized, substantially as shown and described.

HARRY T. JOHNSON.
